SEAL FOR WINDOW SASH

Harold T. Peirson, Brooklyn, N. Y.

Application July 21, 1941, Serial No. 403,388

2 Claims. (Cl. 189—75)

This invention relates to a seal for metallic window sash for the purpose of waterproofing and sealing the sash where it connects to the masonry of the wall and where it connects to metallic mullions. An object of the invention is to provide a waterproof seal in the form of a strip of asphalt which surrounds the metallic part of the sash where it enters the wall or is used between a sash and the mullion. The asphalt is waterproof and durable and in the form of a fabricated strip is easily applied. Another object of the invention is to provide a flexible, pre-formed strip of asphalt which may be applied in the form of a U-shape to the rib of the sash or may be applied in the form of an angle to the sill of the sash. Another object of the invention is to provide for waterproofing the bolt holes securing the sash to the mullion from the strip of asphalt that separates these parts. Other objects of the invention will appear from the following specification and the accompanying drawing, in which:

Fig. 1 is a strip of fabricated asphalt used in carrying out this invention;

Fig. 2 is an end view of a U-shape developed from strip 1;

Fig. 3 is an angular shape developed from Fig. 2;

Fig. 4 is a sectional view of a header construction with the window sash in place;

Fig. 5 is a sectional view of the side of the sash in the masonry;

Fig. 6 is a sectional view of the window sill;

Fig. 7 is a sectional view of a pair of window sashes secured to a mullion; Fig. 8 is a front view of the window sash with the waterproofing strip and Fig. 9 is a section on line 9—9 of Fig. 8.

Figure 10 is a plan view of a fabricated strip with the asphalt partially removed.

In concrete buildings there is liable to be a settling in the masonry which, if not provided for between the metallic sash and the masonry, is likely to distort the sash and may even fracture the glass. Another condition which leads to more disastrous effects arises from the corroding or rusting of metallic or steel window sash where it is built into the masonry. The rust grows in scales arising from the dampness transmitted through the masonry; these scales build up layer upon layer and ultimately lead to a distortion of the window sash or even to fracture of the masonry. Other corrosions also occur which over a period of time affect the usefulness of the sash.

To avoid these conditions the present invention provides a strip of asphalt around the rib of the sash which enters the masonry. This strip is applied to the rib by a waterproof adhesive and is of sufficient thickness to form a pad or cushion for the metal in the masonry that yields to any pressure that may arise from normal building movement or settling. In addition to this the asphalt forms a durable waterproofing medium for the iron of the sash which protects it thoroughly from rusting. A construction of this kind is shown in my co-pending application Serial No. 245,894, filed December 15, 1933, now Patent 2,272,310, February 10, 1942.

In the present invention the asphalt strip which is used in the shape of a U for the rib of the window sash may be re-formed on the ground and applied in the shape of an angle, such as a right angle, to the sill member of the sash before it is erected in the wall, the strip being adjustable to the size of the sill member without trimming.

When the sash is supported by a metallic plate such as a metallic mullion, a strip of asphalt is inserted between the sash and the mullion to seal and waterproof this connection. It is common practice to bolt the sash to the mullion and bolt holes are provided for this purpose. These bolt holes, however, are considerably larger than the bolts to provide for adjustment of the window sash. It is necessary to prevent leakage at the bolt holes so that moisture getting access to the metal at this place cannot spread and develop rust, and so that weather leaks will not occur around the bolts. This condition is effectively avoided by applying a strip of asphalt with an adhesive to the surface of the window sash or the surface of the mullion and opposite the bolt holes to slit it radially so that as the bolt is forced into the hole against the offset asphalt strip the radial projections of the asphalt are carried into the holes. This effectively provides a coating of asphalt for the hole and as the bolt is tightened and the asphalt being somewhat viscous it flows into the space between the bolt and the walls of the hole to make an effective seal which also coats the bolt with the asphalt which helps to retain the nut in place.

The asphalt strips are usually applied to the sash on the ground before it is erected. Asphalt for this purpose has a fabricated structure of a felted or woven member impregnated with the asphalt and coated on the outside with talc or powder to form an outer skin and prevent the layers from adhering to each other in handling.

Prior to this one side of the strip of asphalt may be coated with an adhesive as a rubber cement, and then rolled up for shipment to the place of use. The strip is preferably applied to the metallic surface with a waterproof adhesive, but it can be made adhesive by the application of heat.

When the skin of the asphalt is broken as in the case where it is slit at the bolt holes, the interior asphalt of the strip which is released is adhesive and sticks permanently to the metal. The adhesive holds the surface of the strip to the iron while the soft interior flows under pressure into the hole and is free to fill the hole. The extent to which this result can be secured depends upon the thickness of the asphalt strip and the space between the bolt and the walls of the hole. If the space is too great, or the strip too thin, the hole will not be filled with the free flowing asphalt.

When the strip is applied with threaded bolts in holes which have considerable clearance the threads act as a screw conveyor for distributing the asphalt in the hole.

The fabricated strip of asphalt holds its shape and adheres to the surface of the metal; it does not tend to run under ordinary temperatures.

In the drawing the asphalt strip 31 is folded along the lines *a* and *b* into the U-shape, Fig. 2, with the legs 32 and 33 spaced at *d*, and the V-groove at 34 having the depth *c*. This U-shape is applied as shown in Figs. 4 and 5 to the rib 12 of the sash 11 which supports the glass 14 by the putty 15 on the sash. In Fig. 4 a groove is provided at 22 between the angles 21 of the header which supports the masonry 20, and the rib 12 with the strip 31 is fitted into this space 22. In Fig. 5 the rib 12, with the protecting strip 31 is built directly into the masonry 20 without a form or other preparation. It should be noted that the thickness of the asphalt strip provides for a sliding motion of the sash relative to the masonry, and at the same time the depth of the groove at 34 provides for a large relative movement in this direction.

In the sill construction in Fig. 6 the masonry base 23 tapers off in a slope 24 to shed the water and is built in an upstanding ridge against which the angle 12a of the sill member of the sash 11 is placed as shown with the strip 31 covering both faces of the angle. The strip 31 is the same strip as used in Figs. 4 and 5 but the leg 33 is bent around as indicated by the arrow *e* in Fig. 2 to the angular construction shown in Fig. 3 which fits the angle of the sash. In practice it is desirable that the strip 31 cover the faces of the angle and does not project beyond the angle. At the same time it is not convenient to

trim this material on the ground. The loop formed at the groove 34 is adjustable for this purpose so that it may be flattened out to increase the length of the legs or it may be made larger to take up the surplus. This is readily carried out by the workmen as the installation is being made and the sealing material fills up the corner.

In the mullion construction, Fig. 7, the sash 12 is secured to the plate 29 of the mullion 30 by the bolts 26. The face of the sash adjacent to plate 28 has applied thereon by an adhesive the asphalt strip 25 which forms a seal and cushion for this connection. The sash and the mullion have apertures therein for the bolts 26 and, after the strip 25, Fig. 8, is secured to the sash over the holes 27, radial slits as indicated at 28, are made in the asphalt directly over the holes 27. The bolt is then applied as indicated in Fig. 9 in which the entering end of the bolt forces the radial portions of the fabric into the hole 27 as indicated at 41. The bolt is fully threaded and when it is tightened to compress the strip 25 the asphalt flows into the holes in the space around the bolt as indicated at 40, thereby making a complete waterproof seal at this point. In this operation, the threads of the bolt which are loose in the holes of the plates, also act as a screw conveyor to distribute the asphalt. The fabric 42 is coated on both sides with asphalt 25, and this fabric also is engaged by the threads of the screw and tends to follow the screw in the hole.

The skin of the strip is held in place on the iron by the adhesive while the pressure of the screw clamp forces the asphalt from a considerable area into the space in the hole. The space that may be filled is limited by the amount of free flowing asphalt that can be forced from the strip.

Having thus described my invention, I claim:

1. In combination with a metallic window frame having a sill member of substantially right angle cross section, and a sill to receive the sill member, of means for sealing the joint between the sill member and sill against corrosion and infiltrations, said means comprising a strip of asphalt affixed to both undersurfaces of the sill member by an adhesive, the asphalt strip having a V formed adjacent the center thereof whereby the same is adjustable to different sizes of sill members.

2. A protection for the projecting rib of a metallic window sash against corrosion and infiltrations comprising a pre-formed, substantially U-shaped asphalt cover for said rib having one leg thereof longer than the other leg, and having an inwardly extending groove at the bend of the U-shape.

HAROLD T. PEIRSON.
